(74) *Attorney, Agent, or Firm* — Tarolli, Sundheim, Covell & Tummino LLP; John A. Yirga, Esq.

(57) **CLAIM**

The ornamental design for a truck body roof top, as shown and described.

DESCRIPTION

FIG. 1 is a fully closed upper-right perspective view illustrating my ornamental design for a truck body roof top in accordance with the embodiment;

FIG. 2 is a fully closed upper-left perspective view thereof;

FIG. 3 is a fully closed lower-left perspective view thereof;

FIG. 4 is a fully closed lower-right perspective view thereof;

FIG. 5 is a fully closed right-side elevation view thereof;

FIG. 6 is a fully closed left-side elevation view thereof;

FIG. 7 is a fully closed top-plan view thereof;

FIG. 8 is a fully closed bottom-plan view thereof;

FIG. 9 is a fully closed front elevation view thereof;

FIG. 10 is a fully closed rear-elevation view thereof;

FIG. 11 is a fully opened upper-right perspective view thereof;

FIG. 12 is a fully opened upper-left perspective view thereof;

FIG. 13 is a fully opened lower-left perspective view thereof;

FIG. 14 is a fully opened lower-right perspective view thereof;

FIG. 15 is a fully opened right-side elevation view thereof;

FIG. 16 is a fully opened left-side elevation view thereof;

FIG. 17 is a fully opened top-plan view thereof;

FIG. 18 is a fully opened bottom-plan view thereof;

FIG. 19 is a fully opened front-elevation view thereof;

FIG. 20 is a fully opened rear-elevation view thereof;

FIG. 21 is an upper-right exploded assembly perspective view thereof;

FIG. 22 is a lower-left exploded assembly perspective view thereof; and,

FIG. 23 is a partially opened and partially closed upper-right perspective view thereof.

In the drawings, the broken lines depict environmental subject matter only and form no part of the claimed design.
